EGG TRAY

Walter H. Randall, Waterville, Maine, assignor to Keyes
Fibre Company, Portland, Maine, a corporation of
Maine

Original design application Oct. 2, 1962, Ser. No. 71,962.
Divided and this application Nov. 4, 1963, Ser. No.
77,539

Term of patent 14 years

(Cl. D58—13)

FIGURE 1 is a top plan view of an egg tray embodying my new design;

FIGURE 2 is a cross-sectional view taken along the line 2—2 of FIGURE 1; and

FIGURE 3 is a cross-sectional view taken along the line 3—3 of FIGURE 1.

FIGURE 1 is only partially shaded for convenience of illustration.

This application is a division of application Serial No. D. 71,962 as filed October 2, 1962.

I claim:

The ornamental design for an egg tray, as shown and described.
